UNITED STATES PATENT OFFICE.

MARCIOUS C. RADWAY, OF RIPON, WISCONSIN.

WINDOW-SCREEN.

SPECIFICATION forming part of Letters Patent No. 339,691, dated April 13, 1886.

Application filed February 2, 1886. Serial No. 190,642. (No model.)

To all whom it may concern:

Be it known that I, MARCIOUS C. RADWAY, a citizen of the United States, residing at Ripon, in the county of Fond du Lac and State of Wisconsin, have invented a new and useful Improvement in Window-Screens, of which the following is a specification, reference being had to the accompanying drawings.

My invention relates to improvements in window-screens, and has for its object the provision of an article of the class named adapted to fit windows of different widths, as also those wherein one or both of the sides of the window-frame have been by accident displaced from its or their normal vertical position, to be quickly placed in proper position in the window-opening, securely held therein, and readily removed therefrom, and also to combine cheapness of manufacture, durability of structure, and neatness of appearance.

To these ends the invention consists in the construction, arrangement, and combination of the several parts for service, substantially as hereinafter described, and specifically pointed out in the claims.

In the drawings, Figure 1 represents a side elevation of a window-screen embodying my improvements. Fig. 2 is a top plan view thereof. Fig. 3 represents detached detail views of parts of the improvement.

Referring to the drawings, in which similar letters of reference denote similar parts, A designates the frame of the screen, consisting of the top and bottom rails, a a', and end rails, a'.

b designates a sheet of the ordinary screen-wire placed upon one side of the frame A, and secured thereto by strips b' of wood.

C designates spring-rails that operate at each end of the frame A, upon the surface opposite to that whereon is secured the wire-cloth b.

D designates the springs to which the rails C are connected, and by which said rails are operated. Said springs consist in straight portions d, connected at their outer ends with the rails C, that move freely in longitudinal direction in loops or staples d', affixed to the top and bottom rails, a a', at the ends thereof, as shown, laterally-curved U-shaped spring portions d'', joined by a loop, d'', with the parts d, and straight parts d', the outer ends,

d'', of which are bent inwardly, for the purpose of holding, in connection with staples d'', the spring firmly to the surface of the rail. The parts d d' are in alignment, as shown. 55

I provide each corner of the frame with a spring, D, the U-shaped portion d'' of each of which projects toward the outer edge of the top and bottom rail, respectively, as shown, and extend the part d of said spring to and into the rails C at points d', near the ends thereof, whereby great freedom of movement is imparted to said rails in lateral direction, and whereby either the upper or lower end of the rail C may be pressed outwardly to a greater 65 distance than its opposite end, as shown by dotted lines in Fig. 1. I deem this feature of importance, as thereby the frame or screen may be applied to windows having one or both of the sides of the window-frame out of 70 position, and at angles other than right angles with the window-sill.

It will be observed that the rails C are held solely by the rods d, and that said rails move freely upon the face of the frame. 75

The operation of my improvement will be readily understood without further description.

In order to define the nature and scope of my invention, I would state that heretofore it has been proposed to provide an adjustable window-screen consisting of an ordinary frame having guide-staples at its corners, laterally-movable strips for bearing against the window-frame, and arranged at the side of the end portions of the screen-frame and projecting beyond the same, headed guide-pins secured to the strips and working in the staples at the corners of the frame, and V-shaped springs formed from a single piece of wire, and secured at their apices to the middle of the screen-frame and at their extremities to the movable strips. 85 90

In my improved device I employ the screen-frame and the laterally-movable strips, and the strips are carried and pressed by springs D, of peculiar form, that are secured at each corner of the frame, and I thus dispense with the use of separate guide pins and staples, as has been heretofore common. The springs are 95 100 bent from a single piece of wire, and comprise two straight arms, that are connected by an

intermediate curved or bow-shaped section, one of the arms being secured to the screen-frame and the other arm to the movable strips. The arm d of each spring that connects with the strips is movable longitudinally and guided in staples that are secured to the frame, and by means of the curved section of the spring the arms d and the strips are normally forced laterally of the screen-frame, so as to hold the same very securely in the window-frame. I thus provide a removable and adjustable screen that can be easily and readily adjusted, and which can be manufactured for a trifling sum.

15 I claim—

1. The combination of a screen-frame, the movable pressure-strips independent of the frame, and the springs carrying the strips, and comprising the horizontal arms d d' , connected by an intermediate curved section, the arm d of each spring being secured to the

strips, and the arm d' attached to the screen-frame, substantially as described.

2. As an improved article of manufacture, a window-screen comprising a frame, the 25 movable pressure-strips independent of the frame, and the springs D, arranged at each corner of the frame and carrying the movable strips, said springs being bent from a single piece of wire and having the horizontal arms 30 d d' , and the curved section d^2 , having the coils d^3 , the arms d being secured to the strips and guided in staples on the frame, and the arm d' secured to the screen-frame, substantially as described. 35

In testimony that I claim the foregoing as my own I have hereto affixed my signature in presence of two witnesses.

MARCIOUS C. RADWAY.
